UNITED STATES PATENT OFFICE.

JULIUS H. GILLIS, OF TORONTO, ONTARIO, CANADA, ASSIGNOR TO BRITISH AMERICA NICKEL CORPORATION LIMITED, OF TORONTO, ONTARIO, CANADA, A CORPORATION OF CANADA.

ANODE-CONNECTOR.

1,267,653.

Specification of Letters Patent. Patented May 28, 1918.

Application filed October 15, 1917. Serial No. 196,690.

To all whom it may concern:

Be it known that I, JULIUS HOWELLS GILLIS, a citizen of the United States, residing at Toronto, in the Province of Ontario, 5 Canada, have invented certain new and useful Improvements in Anode-Connectors, of which the following is a specification.

The object of this invention is to provide an improved connecting device for anodes, 10 the same being particularly useful in conjunction with the electrolytic refining of metals or alloys.

In such processes the anodes, consisting of heavy plates of the impure metal to be refined, are commonly suspended in the electrolyte by means of integral upwardly extending cast lugs or ears which rest upon the sides of the tank, at which point the electrical contact is made: or at times the 15 integral lugs project only slightly above the liquid, connections for suspending the anode and making electrical contact therewith being made to these short lugs in various ways. Such methods possess the disadvantages that the lugs represent a material proportion of undissolved scrap or waste requiring re-melting; that breakage of the lugs is frequent owing to the low and variable tensile strength of the impure metal; 20 and that anodes having such lugs are difficult to cast and handle.

It has not heretofore proven practical to make the connection to the anode below the solution line, because the hangers, functioning also as connectors, have a strong tendency to be dissolved and destroyed, this tendency being especially marked in those parts of the hanger which project nearer to the cathode than the main anode surface. 25 The use of lead or lead-covered hangers in sulfate solutions has been suggested, but has not proven satisfactory on account of the softness and low tensile strength of lead, and especially because the tendency still remains 30 for deposits to build up on the cathode opposite any projecting portions of the hanger, quickly forming short-circuits.

I have discovered that by constructing the anode connectors of aluminum most or all of 35 the difficulties above enumerated may be avoided. I use these aluminum connectors in electrolytes, for example sulfate or sulfuric acid or other appropriate solutions, capable of forming by anode action a practically non-conductive surface film upon the

aluminum, or of conserving such a film after its formation. The invention is therefore based on the known fact that aluminum, when made the anode in a suitable electrolyte, has the peculiar property of protecting 60 itself with a thin coating of hydrate, basic sulfate, phosphate or other compound, according to the electrolyte used, this deposit not only preventing further solution of the metal, but also insulating the metal from the 65 solution and thereby preventing the flow of the electric current from the connector or hanger to the adjacent portions of the cathode.

It will be readily understood from the foregoing that my invention is not restricted to any particular form or shape of anode connector or hanger, since the principle involved may be applied advantageously in many forms.

In the accompanying drawing, in which— Figure 1 is a transverse vertical section through a refining tank provided with my improved connector; and

Fig. 2 is a vertical section of an anode and connector on line 2—2 of Fig. 1, I have illustrated one preferred embodiment of the invention.

In said drawing, 1 represents the tank, and 2 an anode of impure copper, nickel or other metal or alloy to be refined, said anode cast with lateral ears 3, 3, and being wholly submerged beneath the solution level indicated at 4. The anode connector, which may be an integral aluminum casting, comprises a bar 5 contacting with a conductor 6 on the tank wall, and provided with depending supporting lugs 7, 7, each having at its lower end a bifurcated hook 8 adapted to engage the ears 3 of the anode.

It has been found in practice that considerable resistance is apt to develop at the surface of contact between the aluminum connector and the anode. Although this resistance is not sufficient to cause the current 100 to flow directly from the aluminum to the solution, or to render the device practically inoperative, I prefer to overcome it by casting into the aluminum, at the areas of contact with the anode, small copper or other 105 appropriate conductive blocks or contact points, for example as indicated at 9. Thereby, I provide a positive electrical connection between the aluminum and the copper contact piece, and permit the copper to make 110

the (normally) less perfect contact with the anode. This provision of a special contact point is not however essential to the invention, and the invention is therefore not restricted to this specific construction. Obviously, the contact point, when used, may be of any suitable metal or conductive substance, appropriate for the particular electrolyte and refining operation.

16 Obviously, since the function of the aluminum connector depends upon an anodic surface action, any anode connector presenting aluminum surfaces to the electrolyte is equivalent, for the purposes of this invention, to the aluminum hangers described herein. In form these connectors will be varied to suit the service required of them: for example, aluminum wire or rod baskets may be used for scrap anodes, and like structural modifications will be made to suit other special conditions, without departing from my invention.

In some cases the aluminum connector

may serve also as the support for the anode; or, especially in the case of heavy or weak anodes, these may be otherwise supported in any suitable way, as for example by resting on insulating blocks 10. In either case the aluminum functions as the electrical connection for the soluble anode.

25

30

I claim:

1. In combination with a soluble anode and a suitable electrolyte, an anode connector of aluminum.
2. In combination with a soluble anode 35 and a suitable electrolyte, an anode connector of aluminum having secured therein one or more contact pieces of a conductive material other than aluminum.
3. In combination with a soluble anode 40 and a suitable electrolyte, an anode connector of aluminum having secured therein one or more contact pieces of copper.

In testimony whereof, I affix my signature.

JULIUS H. GILLIS.
